HYDRAULIC JACK

Louis Berg, Birmingham, Mich.

Application September 21, 1946, Serial No. 698,522

2 Claims. (Cl. 254—93)

1

This invention relates to improvements in hydraulic jacks and in particular to improved hydraulic bumper jacks for automobiles.

The primary object of the invention is to provide an improved hydraulic jack in which the entire hydraulic pumping and valve mechanism is located in a novel, compact and readily manufactured head.

Another object of the invention is to provide an improved hydraulic bumper jack in which the bumper engaging means is readily adjustable to the bumper prior to the jack being operated to lift an automobile.

A further object of the invention is to provide an improved hydraulic bumper jack which is simple in construction, positive in operation and inexpensive to manufacture.

Other objects of the invention will become apparent by reference to the following detailed description taken in connection with the accompanying drawing, in which:

Fig. 1 is a side elevational view of a hydraulic bumper jack embodying the invention with portions thereof broken away to illustrate the construction.

Fig. 2 is a horizontal sectional view taken on the line 2—2 of Fig. 1.

Fig. 3 is a horizontal sectional view taken on the line 3—3 of Fig. 1.

Fig. 4 is a fragmentary sectional view taken on the line 4—4 of Fig. 2.

Referring now to the drawing wherein like numerals refer to like and corresponding parts throughout the several views, the particular embodiment of the invention disclosed for the purpose of illustration comprises a base 10, a generally vertically disposed piston 11 having a ball 12 formed on the lower end thereof engaged in a socket 13 formed in the said base 10, a cylinder 14 into which the piston 11 is reciprocatingly mounted, a housing 15 forming a reservoir 16 for oil or other fluid around the said cylinder 14 sealed with respect to the said cylinder 14 at the lower end thereof, a pump head 17 mounted in operating sealed relationship on top of the said cylinder 14 and housing 15, an eduction tube 18 extending from the said pump head 17 to a point near to the bottom of the said reservoir 16, the said cylinder 14 having a by-pass 19 therethrough located near the bottom thereof for limiting the upward movement of the said cylinder 14 with respect to the piston 11, and a manually operated lowering valve 20 connecting the reservoir 16 with the upper end of the said cylinder 14 for lowering the said housing 15 under load, an adjustable bumper engaging arm 21 slidably mounted on said housing 15, and a cam 22 for releasably securing the said slidably

2

bumper engaging arm 21 at the desired elevation on the said housing 15.

The top of the vertically disposed piston 11 has a self sealing head 23 of neoprene, leather or the like secured on the upper end thereof which is suitably lipped to flex against the wall of the cylinder 14 and provide a seal between the top of the piston 11 and the cylinder 14 when fluid under pressure is forced from the pump head 17 into the cylinder 14. The said piston head 23 has washers 24 and 25 disposed above and below the base thereof and is secured to the top of the piston 11 by means of a stud 26. The bottom of the cylinder 14 and the bottom of the housing 15 are fixed in sealed relationship to a guide sleeve 27 disposed around the piston 11. Packing 28 squeezed between the lower end of the cylinder 14 and a packing nut 29 slidably disposed over the piston 11 and threaded into the guide sleeve 27 prevents leakage of fluid from the lower end of the said cylinder 14 as it moves upwardly and downwardly with respect to the piston 11. The upper end of the cylinder 14 is threaded at 30 into a cylindrical recess provided in the bottom of the pump head 17 and the housing 15 is pressed, brazed or otherwise secured at 31 to the lower end of the said pump head 17, all as best shown in Fig. 1.

The bumper engaging arm generally designated 30 by the numeral 21 in Fig. 1 comprises a sleeve 32 slidably disposed on the housing 15 with a pair of laterally spaced laterally protruding hooks 33 adapted to engage a bumper of an automobile formed integral with the said sleeve 32 and extending laterally therefrom. A pin 34 extends through both of the said spaced protruding hooks 33 near the housing 15 and has journaled thereon an eccentric or cam 22 having an operating lever 35 fixed thereto. By moving the operating lever 35 from the full line position shown in Fig. 1 to the dot and dash line position 350, the cam 22 is brought into engagement with the housing 15 and the bumper engaging arm 21 becomes removably fixed with respect thereto.

45. The pump head 17 comprises a cylindrical lower portion 36 and a pair of laterally spaced rectangular upright members 37 integral therewith connected at their top by a bridge 38. Each upright member 37 is vertically bored from the top thereof and lined with tubular liners 39 to form cylinders 40 and 41 which are fitted with pistons 42 and 43. The upper end of each piston is flattened at 44 to accommodate links 45 which are connected by link pins 46 and 47 to the pistons 42 and 43 and the rocker arm 48 respectively. The said rocker arm 48 is pivoted on a transverse fulcrum pin 49 which extends through the rocker

arm 48 and the bifurcated fulerum support 50. The end 480 of the rocker arm 48 which is broken away in Fig. 1 extends outwardly a sufficient distance to serve as a lever for pivoting the said rocker arm 48 about its fulcrum 49, thus causing the pistons 42 and 43 to reciprocate in the cylinders 40 and 41 respectively.

A suitable annular gasket or packing 51 of neoprene or the like is positioned around each piston 42 and 43 and is squeezed between the upper ends of the liners 39 and a packing nut 510 threaded in the upper end of each cylinder 40 and 41 to provide a leakproof joint around the said pistons 42 and 43. Each piston 42 and 43 is preferably shouldered at its lower end 52 and has a central depending button 53 formed on the lower end thereof over which is disposed a cup shaped self sealing piston head 54 of neoprene, leather or the like which is suitably lipped to flex against the walls of the cylinders 40 and 41 to provide a seal between the top of the pistons 42 and 43 and the said cylinders 40 and 41 respectively during the compression stroke of the said pistons 42 and 43.

Each of the cylinders 40 and 41 is provided with a vertically disposed inlet port 56 and 57 respectively which are connected by a transverse inlet passage 55 to a vertical inlet passage 560 which in turn is connected to the eduction tube 18 which extends to a point near the bottom of the reservoir 16 located between the cylinder 14 and the housing 15. Normally closed spring loaded ball check valves 58 and 59 are disposed in the transverse inlet passage 55 between the vertical inlet passage 560 and the vertical inlet ports 56 and 57 of the cylinders 40 and 41 respectively, all as best shown in Figs. 1, 2, 3 and 4.

Each of the cylinders 40 and 41 is also provided with vertically disposed outlet ports 60 and 61 respectively which are connected by transverse outlet passages 62 and 63 to vertical outlet passages 64 and 65 normally closed by spring loaded ball check valves 66 and 67 which are urged closed by a common inverted cone spring 68 disposed between the head of a stud 69 and a rocker washer 70 which maintains either one or both of the said ball check valves 66 and 67 closed at all times, all as best shown in Figs. 1, 2 and 3.

After the jack has lifted an automobile by its bumper or other object to the desired height, the hydraulic jack is lowered by turning the lowering valve 20 to the position indicated in Fig. 1 with the passages 71 and 72 in communication with each other whereby to let fluid flow from the cylinder 14 above the head 23 of the piston 11 to the reservoir 16. Obviously, during pumping to raise the jack, the lowering valve 20 is closed by turning the same 90 degrees from its position shown in Fig. 1.

From the foregoing detailed description, the operation of the hydraulic bumper jack is obvious, the improved construction being simple and inexpensive to manufacture and requires substantially no maintenance.

Although but one embodiment of the invention has been disclosed and described in detail, it is obvious that many changes may be made in the size, shape, arrangement and detail of the various elements of the invention without departing from the spirit and scope thereof as defined by the appended claims.

I claim:

1. A hydraulic jack comprising a base, a piston connected to said base extending upwardly therefrom, a piston head on said piston, a cylinder sub-

stantially coextensive of said piston reciprocatingly mounted over said piston, a housing over said cylinder, a pump head on said housing and said cylinder forming a reservoir around said cylinder including an eduction tube extending into the said reservoir to a point substantially at the bottom thereof, a multi-piston pump in said pump head including intake and outlet valves for each pump cylinder between the said reservoir and the said jack cylinder respectively employed to withdraw fluid from said reservoir and force the same into said cylinder above said piston head whereby to raise the said cylinder and housing on said piston with respect to the said base, an independent spring urging each intake valve closed, a rocker washer bridged between the said outlet valves and a common spring acting through said rocker washer urging said outlet valves closed and permitting either one or the other to open, means slidably adjustable along said housing adapted to be removably fixed to the desired position therealong for engaging objects of various heights, and a manually operated lowering valve normally closed which when open permits fluid to flow from said cylinder to said reservoir responsive to weight lifted by said jack.

2. A hydraulic jack comprising a base, a piston connected to said base extending upwardly therefrom, a piston head on said piston, a cylinder substantially coextensive of said piston reciprocatingly mounted over said piston, a housing over said cylinder, a pump head on said housing and said cylinder forming a reservoir around said cylinder including an eduction tube extending into the said reservoir to a point substantially at the bottom thereof, a multi-piston pump in said pump head including intake and outlet valves for each pump cylinder between the said reservoir and the said jack cylinder respectively employed to withdraw fluid from said reservoir and force the same into said cylinder above said piston head whereby to raise the said cylinder and housing on said piston with respect to the said base, an independent spring urging each intake valve closed, a rocker washer bridged between the said outlet valves and a common spring acting through said rocker washer urging said outlet valves closed and permitting either one or the other to open, the said cylinder having a by-pass therethrough near the bottom thereof whereby to cause fluid to circulate from said cylinder to said reservoir after the said cylinder and housing have been raised to a predetermined height, means slidably adjustable along said housing adapted to be removably fixed to the desired position therealong for engaging objects of various heights, and a manually operated lowering valve normally closed which when open permits fluid to flow from said cylinder to said reservoir responsive to weight lifted by said jack.
